United States Patent Office.

CHARLES BEMIS, OF MISHAWAKA, INDIANA.

Letters Patent No. 65,718, dated June 11, 1867.

IMPROVEMENT IN PUMPS.

The Schedule referred to in these Letters Patent and making part of the same.

TO ALL WHOM IT MAY CONCERN:

Be it known that I, CHARLES BEMIS, of Mishawaka, in the county of St. Joseph, and in the State of Indiana, have invented certain new and useful Improvements in Hydraulic Pumps; and do hereby declare that the following is a full, clear, and exact description thereof reference being had to the accompanying drawings, and to the letters of reference marked thereon.

In the annexed drawings making part of this specification, A represents a box, with an open bottom, in which the operating devices of the pump are placed. B B' represent two cylinders which are secured in the box A in a horizontal position, with their heads facing each other, and a short distance apart. J J represent two piston-heads, which are provided with openings through their centres, which said openings are covered by suitable valves. These piston-heads fit snugly in the cylinders B B'. b b' are piston-rods which run through the cylinder-heads, and connect with their inner ends to the piston-heads J J. The outer ends of the rods b b' are secured to the lower end of a lever, E. D represents a pipe which is situated within the box A, and which has an elbow, D', at each end. These elbows lead into the cylinders B B' near their outer ends. A pipe, C, which leads into the water of the well or cistern, connects to the pipe D at its centre, and on each side of its point of connection within the pipe D are two valves c c'. A pipe, H, similar to pipe D, is also situated within the box A. This pipe H has two elbows H', which enter the cylinders near their inner ends, and has connected to it at its centre a pipe, G, which leads up and delivers the water which is drawn from the well. Valves are placed in the elbows H' H'. A narrow box, A², is secured upon top of the box A which encases the lever E. The lever E is provided at its upper end with a long slot, in which one end of a crank-shaft, F, plays to give it an oscillating motion. The crank-shaft F has its bearing and is confined in one side of the narrow box A².

In drawing water with this device, the crank-shaft F is turned, which gives an oscillating motion to the lever E, and as said lever works it causes the piston-heads J J to play backward and forward in the cylinders B B'. These piston-heads draw water through the pipes D and C at one stroke, and discharge it through pipes H and G at the other, thus causing a continuous flow of water from the well or cistern. This apparatus can be used as a pump, or by attaching hose to the mouth of the discharge pipe it may be used as an engine for throwing water in case of fire.

Having thus fully described my invention, what I claim as new, and desire to secure by Letters Patent, is—

The arrangement herein set forth of the cylinders B B' with their piston-heads and rods, the pipes D and H with their valves, and the slotted lever E with its crank, all constructed and used with the boxes A A², as and for the purpose herein specified.

In testimony that I claim the foregoing I have hereunto set my hand and seal this sixth day of March, 1867.

CHARLES BEMIS.
